ELECTRIC PHONOGRAPH

Kiyoshi Shindo, Habikino-shi, Japan, assignor to Sharp
Kabushiki Kaisha, Osaka, Japan

Filed Mar. 30, 1973, Ser. No. 346,325

Term of patent 14 years

Int. Cl. D14—01

U.S. Cl. D56—4 R

FIG. 1

FIG. 2

FIG. 3

FIG. 4

FIG. 5

FIG. 6

FIG. 7

FIG. 1 is a top perspective view of an electric phonograph with the case open showing my new design;

FIG. 2 is a right side elevational view with the case closed;

FIG. 3 is a bottom plan view thereof;

FIG. 4 is a rear elevational view thereof;

FIG. 5 is a top plan view thereof;

FIG. 6 is a front elevational view thereof; and

FIG. 7 is a front, top and right side perspective view thereof.

Portions of the figures are diagonally lined to indicate transparency, and structure which would be visible through the transparent cover in FIGS. 2 and 4-7 has been omitted for convenience of illustration.

I claim:

The ornamental design for an electric phonograph, as shown and described.
